UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

WIRE-TIE-FORMING MACHINE.

1,162,675.

Specification of Letters Patent.

Patented Nov. 30, 1915.

Application filed August 26, 1914. Serial No. 858,584.

To all whom it may concern:

Be it known that I, ADELMER M. BATES, a citizen of the United States, residing at Chicago, in the county of Cook and State of Illinois, have invented a certain new and useful Improvement in Wire-Tie-Forming Machines, of which the following is a specification.

My invention relates to improvements in means for forming wire ties and the like having particular reference to grouping the successive forming wire ties in a belt or band arrangement.

It is illustrated more or less diagrammatically in the accompanying drawing, where-

Figure 1 is a front elevation of a machine with parts omitted and parts in section; Fig. 2 is a section along the line 2—2 of Fig. 1; Fig. 3 is a section along the line 3—3 of Fig. 1; and Fig. 4 is a section along the line 4—4 of Fig. 3; Fig. 5 is a detail vertical section of the mandrel shown in modified form; and Fig. 6 is a plan view of the finished tie.

Like parts are indicated by like letters throughout the several figures.

A is a main frame upon which are mounted two bracket arms A¹, A². These bracket arms contain each a vertically disposed rotatable sleeve A³, A⁴ having gears A⁵ mounted thereon. These gears are in engagement with a rack A⁶ which may be reciprocated by any desirable means not here illustrated to rotate the sleeves.

A⁷, A⁸ are forming mandrels held against rotation but slidable within the sleeves A³, A⁴.

A⁹ is a rock arm mounted on the rock shaft A¹⁰ which may be rocked by any suitable means not here shown to reciprocate the forming mandrels at the proper time to withdraw them from the wire tie and cause it to drop from the mandrel by pressing it against the end of the sleeves A³, A⁴.

A¹¹, A¹² are twisting fingers mounted on the sleeves A³, A⁴ and adapted to engage the wire A¹³ and twist it about the mandrel as they rotate.

B is a twisting mandrel through which the wire A¹³ projects and is adapted to be rotated by the gear B¹ driven by any suitable means not shown to complete the tie by twisting its ends around the wire thus forming eyes at these ends. It will be noted that

the finger A¹¹ moves from the position shown in Fig. 3 in full lines to that shown in dotted lines to bend the wire shown in dotted lines, whereupon the mandrel B rotates to bend the free end up around the wire. 60 The rotation of the fingers A¹¹, A¹² is substantially through an angle of 270°, thus for 90° the forming mandrel is not quite covered by this finger.

C is a slot or groove in the end of the 65 mandrel A⁷ extending upwardly from the end for a short distance. Through this slot is looped a cord C¹ which comes from the reel C² and passes through the eyelet C³ and down over the roller C⁴ passing through 70 and holding together the adjacent ties C⁵ as they are fed from the machine. These ties are thus held by the cord in a belt which is wound around the roller. It will be noted that each eye is formed about the string or 75 cord so that as the ties are discharged each tie is held in position and cannot escape.

In the modified form shown in Fig. 5 the outside wall of the slot C is closed up to form an aperture or passage through or 80 within the mandrel adjacent its forming end through which the string may be made to pass.

It will be evident that while I have shown in my drawings an operative device, still many 85 changes might be made both in size, shape and arrangement of parts without departing from the spirit of my invention, and I wish, therefore, that my drawings be regarded as in a sense diagrammatic.

It will be understood that these wire ties are those looped wire ties which are so common when applied as closures for sacks and the like. It will be understood that in operation they are used by a tool which enters, 95 the loops at either end of the tie and draws the tie around the bag or other object to be tied. The tool then twists the ends of the tie together, thus forming a centrally constricted loop leaving the two eyes bearing 100 ends projecting outwardly as keys, whereby an operator who wishes to unload or release an object may turn or twist in the opposite direction to get the desired releasing result.

I have used the term "a forming zone." 105 It is understood that this zone means that small area about each of the two vertical mandrels where the forming takes place. It is an area wherein considerable pressure is applied to the mandrel by the wire and 110

finger, and in that zone or area the twisting, forming or looping of the tie takes place.

I claim

- 5 1. In a wire tie forming machine, a mandrel, slotted to permit passage of a cord therethrough, and means for forming a wire tie about said mandrel to inclose the cord.
- 10 2. In a wire tie forming machine, a mandrel, slotted to permit passage of a cord therethrough, means for forming a wire tie about said mandrel to inclose the cord, a frame, and means for winding up successive ties in a belt thereupon.
- 15 3. In a wire tie forming machine, a mandrel, slotted to permit passage of a cord therethrough, a guide for the cord, and means for forming a wire tie about said mandrel to inclose the cord.
- 20 4. In a wire tie forming machine, a mandrel, slotted to permit passage of a cord therethrough, means for forming a wire tie

about said mandrel to inclose the cord, and means for discharging successive ties from the mandrel along the cord.

5. In a wire tie forming machine, a mandrel apertured adjacent its forming end, to permit passage of a cord therethrough, and means for forming a wire tie around the cord. 25

6. In a wire tie forming machine, a mandrel apertured to permit passage of a cord therethrough, a forming zone about said mandrel, said aperture being closed at the forming zone but open on both sides of it. 30

In testimony whereof, I affix my signature 35
in the presence of two witnesses this 20th
day of August 1914.

ADELMER M. BATES.
